US00D995182S

(12) **United States Design Patent** (10) **Patent No.:** **US D995,182 S**
Guo (45) **Date of Patent:** **** Aug. 15, 2023**

(54) **PROTEIN SHAKER**

(71) Applicant: **SHENZHEN BALOGZON IMPORT AND EXPORT TRADE CO., LTD,**
Shenzhen (CN)

(72) Inventor: **Yushi Guo**, Shenzhen (CN)

(73) Assignee: **SHENZHEN BALOGZON IMPORT AND EXPORT TRADE CO., LTD,**
Shenzhen (CN)

(**) Term: **15 Years**

(21) Appl. No.: **29/817,746**

(22) Filed: **Dec. 3, 2021**

(51) **LOC (14) Cl.** **07-01**

(52) **U.S. Cl.**

(57) **CLAIM**

The ornamental design for a protein shaker, as shown and described.

DESCRIPTION

FIG. 1 is a perspective view of a protein shaker showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the protein shaker that form no part of the claimed design.

1 Claim, 8 Drawing Sheets
